UNITED STATES PATENT OFFICE.

LAZAR LAZARUS, OF INDIANAPOLIS, INDIANA.

FEED-BAG SUPPORT.

1,161,700.

Specification of Letters Patent.

Patented Nov. 23, 1915.

Application filed February 19, 1915. Serial No. 9,412.

To all whom it may concern:

Be it known that I, LAZAR LAZARUS, a citizen of the United States, residing at Indianapolis, in the county of Marion and State of Indiana, have invented certain new and useful Improvements in Feed-Bag Supports, of which the following is a specification.

This invention relates to a device which is intended to support a feed receptacle such as a bucket or the like and the principal object of the invention is to so construct the support that it may be connected with the shaft of a vehicle or may be connected with the body of the horse if the horse is connected with a vehicle not provided with shafts.

Another object of the invention is to so construct this device that it may be easily converted from one position to another according to the use to which it is to be put.

Another object of the invention is to so construct this support that it may be folded into a compact mass when it is desired to put the same away.

Another object of the invention is to so construct this device that it may be formed almost entirely of sheet metal or the like, the various parts being pivotally connected and thus producing a structure.

Another object of the invention is to provide a device of the character described which will be very simple in construction and at the same time very strong and durable.

This invention is illustrated in the accompanying drawings, wherein:—

Figure 1 is a view in side elevation showing the device applied to a horse. Fig. 2 is a perspective view showing the device applied to the shaft of a vehicle. Fig. 3 is a view in side elevation showing the support in the folded position. Fig. 4 is a top plan view showing the device in the folded position. Fig. 5 is a fragmentary view showing the manner of mounting the cross bar forming part of this device.

The shafts 10 of the vehicle must be provided with the buttons or pins 11 and 12 so that when it is desired to connect this device with the shafts the buttons may be passed through the bayonet slots 13 and 14 leading from the upper and lower edges of the supporting bars 15 to releasably connect the support with the shaft. Openings 16 are formed in the ends of the supporting

bars 15 so that a strap 17 may be passed through the free ends of these supporting bars to hold the same against the sides of a horse as shown in Fig. 1 thus supporting the device from the horse with the strap resting upon the back of the horse just at the base of the horse's neck.

The carrying bars 18 are pivotally connected with the supporting bars 15 through the medium of the pivots 19 and are provided with abutment ears 20 which engage the lower edges of the supporting bars 15 when the supporting bars are extended as shown in Fig. 2 thus preventing the carrying bars from falling forwardly beyond the horizontal position. When it is desired to connect this supporting device directly with the horse it is desirable to have the supporting bars 15 extending horizontally but at an angle to the connecting bars 18 and therefore there has been provided the bracing links 21 which are pivotally connected as shown at 22 and pivotally connected with the supporting bars 15 as shown at 23. The pivots 24 which connect the links 21 with the bars 18 pass through the slots 25 in the bars 18 and therefore these links will be slidably as well as pivotally connected with the supporting bars. From an inspection of Fig. 2 it will be noted that each of these slots 25 is provided with an extension forming a pocket 26 so that the pins 24 may move into the pockets 26 and prevent the bars 18 from moving out of the horizontal position shown in Fig. 1. In order to prevent this feed bag holder from moving rearwardly along the horse's back there has been provided the rod or bar 27 which has its end portions passed through the openings of the ears 28 and extends transversely between the two sets of links 21 so that the bar will engage the horse's chest and thus limit the rearward movement of the supporting frame upon the animal.

The feed receptacle which may be in the form of a bucket 29 or any other suitable receptacle is placed in the hoop 30 which is pivotally mounted between the outer ends of the carrying bars 18 by means of the pivot pins 31. This hoop 30 is formed of the major sections 32 and auxiliary sections 33, the two sections 32 and the two sections 33 being hingedly connected as shown at 34 and the sections 33 being pivotally connected with the sections 32 by means of the pivots 35. It will therefore be seen that when

it is desired to fold up the frame the sections 33 may be turned within the sections 32 and the free ends of the sections 32 and 33 then brought toward each other as shown in Fig. 4.

When in use the support may be used as shown in Fig. 1 or may be used as shown in Fig. 2. If it is used as shown in Fig. 1 the attaching bars 15 will be raised and the pivots 24 moved into the pockets 26. The free end portions of the attaching bars 15 will then be connected by the strap 17 and the horse's head passed between the attaching bars with the strap resting upon the horse's back adjacent the base of the horse's neck. The frame will now be held in the position shown by the bar or rod 27 and the feed bag or bucket 29 can be placed in the hoop 30 where it will be positioned as shown in Fig. 1 within easy reach of the horse. If this device is used as shown in Fig. 2 the strap 17 and cross bar 27 will not be used and the attaching bars 15 will be moved to the extended position shown with the links extending 25 against the outer faces of the bars 15 and 18. The device will then be put in place with the pins 11 and 12 fitting into the bayonet slots 13 and 14 and the feed receptacle placed in the hoop 30 where it will be positioned in front of the horse in substantially the same relation to the horse as shown in Fig. 1. The bars and links and the sections from which the hoops are made will be stamped from light sheet metal and therefore this supporting frame will not be heavy or unwieldy to handle thus permitting a person to very easily put the frame in place at feeding time. After the horse has been fed the supporting frame is removed 30 from the animal or from the shafts and the attaching or connecting bars 15 are bent forwardly with the links doubled as shown in Fig. 3. The hoop sections 33 are then turned to the position shown in Fig. 4 and 35 the frame will be collapsed and can be put away in a convenient place until it is again desired to use the same. Therefore this frame will not take up a great deal of room as it can be folded into a very compact mass. It is of course obvious that if desired the hoop sections 32 could be left in the position shown in Fig. 2 instead of being turned inwardly as shown in Fig. 4 when holding this frame it being optional with the operator as 50 to whether the hoop will be folded to extend between the bars 18 or beyond the same.

It will thus be seen that I have provided a feed receptacle supporting frame which can be easily connected with the shaft as 55 with the horse and which is so constructed that it may be folded into a compact mass when no longer in use. It will also be noted that when the device is connected with the horse it will remain in the stationary position thus preventing danger of the frame

slipping out of place and bringing the feed receptacle too close to the animal. It will also be noted that practically all of the parts to this machine may be struck from sheet metal and therefore it can be produced at a comparatively small cost. It will be further noted that due to its construction there are few parts to get out of order and therefore the device is not liable to become broken or need repair.

What is claimed is:—

1. A supporting device of the character described comprising a receptacle receiving hoop, carrying bars pivotally connected with said hoop, suspending bars pivotally connected with said carrying bars, and bracing links pivotally connected with one set of bars and slidably connected with the other set of bars.

2. A supporting frame of the character described comprising receptacle holding means, carrying bars pivotally connected with said receptacle holding means, suspending bars pivotally connected with said carrying bars, links pivotally connected with said suspending bars, and links pivotally and slidably connected with said carrying bars and pivotally connected with said first mentioned links.

3. A frame of the character described comprising receptacle holding means, carrying bars extending from said receptacle holding means, suspending bars extending from said carrying bars, flexible means connecting the free end portions of said suspending bars, and bracing links pivotally connected with said suspending bars and pivotally and slidably connected with said carrying bars.

4. A frame of the character described comprising receptacle holding means, carrying bars extending from said receptacle holding means and provided with longitudinally extending slots having offset portions forming pockets, suspending bars pivotally connected with said carrying bars adjacent the free ends thereof, links pivotally connected with said suspending bars, links pivotally connected with said first mentioned links, pivot means for said last mentioned links passing through the slots of said carrying bars and moving into said pockets to releasably hold said links in an adjusted position, rigid means releasably connected with said last mentioned links and extending transversely between the same, and flexible means connecting the free end portions of said suspending bars.

5. A frame of the character described comprising receptacle holding means, carrying bars extending from said receptacle holding means and provided with longitudinally extending slots having offset portions forming pockets, suspending bars pivotally connected with said carrying bars,

bracing links pivotally connected with said suspending bars, pivot means for said links passing through the slots of said carrying bars, rigid means connecting said links and holding said carrying arms in spaced relation, and means for connecting the free ends of said suspending bars.

6. A frame of the character described comprising receptacle holding means, carrying bars extending from said receptacle holding means and provided with slots having offsets forming pockets, suspending bars connected with said carrying bars, and bracing links pivotally connected with said suspending bars and provided with pins slidably mounted in the slots of said carrying bars and fitting into the offsets thereof.

7. A device of the character described comprising carrying means, receptacle holding means positioned between said carrying means, said receptacle holding means comprising major sections hingedly connected together and pivotally connected with said carrying means, and auxiliary sections hingedly connected together and pivotally connected with said major sections to permit the auxiliary sections to be swung into

the space between the free end portions of said major sections.

8. A device of the character described comprising carrying means, receptacle holding means positioned between said carrying means, said receptacle holding means comprising major sections hingedly connected and pivotally connected with said carrying means, auxiliary sections hingedly connected and pivotally connected with said major sections to permit said auxiliary sections to be swung into the space between the free end portion of said major sections, suspending means connected with said carrying means, and bracing means connected with said carrying and suspending means.

9. A device of the character described comprising carrying means, and collapsible receptacle holding means connected with said carrying means.

In testimony whereof I affix my signature in presence of two witnesses.

LAZAR LAZARUS.
